UNITED STATES PATENT OFFICE

HARRY M. HENDERSON, OF WASHINGTON, DISTRICT OF COLUMBIA

COIN-CONTROLLED MECHANISM

Application filed December 9, 1927. Serial No. 288,816.

My present invention relates generally to coin controlled apparatus and has to do more particularly with such apparatus as applied to, and used in connection with, the dispensing of cups and a measured quantity of beverage into each cup, and my primary object is the provision of an apparatus whereby the desired result may be accomplished in a simple effective manner with little, if any, likelihood of success by the use of slugs or coins of other than the size required for its proper operation.

A further object is the provision of a mechanism which is compact, strong and durable, which may be formed and installed as a unit and may, for this reason, be removed as such so as to permit of ready adjustment, repair and substitution of parts.

A still further object of the invention is the provision of a mechanism embodying means whereby upon each operation, the coin used to promote the same will be positively displaced so as to avoid the possibility of a second operation by the use of a burred or otherwise misshapen coin.

With the above general objects in mind, the further and more specific objects of my invention, as well as the structure, arrangement and operation of the parts, and the resulting advantages thereof will appear in the course of the following description, reference being made to the accompanying drawings, which form a part of this specification, and in which,

Figure 1 is a sectional top plan view of the complete mechanical unit embodying my invention.

Figure 2 is a vertical cross section taken therethrough substantially on line 2-2 of Figure 1.

Figure 3 is another vertical cross section taken on line 3-3 of Figure 1.

Figures 4 and 5 are vertically longitudinal sections taken respectively on lines 4-4 and 5-5 of Figure 3.

Figure 6 is a detail horizontal sectional view taken substantially on line 6-6 of Figure 5.

Figure 7 is a vertical longitudinal section

showing certain of the parts of Figure 5 in actuated position.

Figure 8 is a horizontal sectional view showing certain parts for the actuation of the beverage measuring valve.

Figure 9 is a detail vertical section taken through the cup discharge spout.

Figure 10 is a detail perspective view of the controlling weight of the cup holder;

Figure 11 is a vertical sectional view showing certain of the closure operating connections of the cup discharge spout.

Referring now to the above identified drawings, I have shown at A, a conventional form of cup dispensing apparatus mounted at the lower end of an elongated upright cup holding tube B which I have, for the purposes of my invention, provided with a vertical slot B' to receive the radially outstanding rib C' of a controlling weight C. This weight is in practice placed upon a series of nested cups in the holder B and its rib C' supports an arcuate sign plate C² upon the exterior of the tube. Thus the weight C will gradually drop in the tube as the cups are dispensed by the apparatus A through the swinging actuation of its arm A', and will in its lowermost position engage and depress one end of a controlling arm or lever 15 pivoted intermediate its ends as at 16 upon the cup dispensing apparatus, for a purpose which will presently appear. In practice, the casing or housing in which the parts just described are mounted, may have

a window and the like so located as to bring the sign plate C² into view in the lowermost position of the controlling weight C, so that the legend, preferably the word "Empty" may be easily seen.

I also preferably provide the lower portion of the cup dispensing apparatus A, with a depending extension or discharge tube 17 adapted in practice to guide the cups, as they are dropped, to a position below and at one side of the apparatus A to facilitate their disposition below a fluid discharge tube D. Since for practical purposes the lower end of the cup dispensing apparatus must be exposed, I preferably avoid unwarranted re-

removal of the cups by providing the discharge tube 17 with closure member 18 of the concavo-convex form shown in Figures 3 and 9. This shutter like closure 18 which in its normal position extends in an approximately horizontal position across the discharge tube 17, as in Figure 9, so as to prevent the insertion of the hand upwardly into the cup dispensing apparatus, is fixed 10 at one point to a rock-shaft 19 journaled in the side wall of the discharge tube 17 and provided with an outstanding crank arm 20. This crank arm upon actuation, as herein-after described, throws the closure 18 downwardly to the dotted line portion of Figure 15 9, its shape permitting it to conform to the inner surface of the discharge tube 17 so as to permit a cup to freely drop through the tube 17 when released by actuation of the 20 cup dispensing mechanism A.

Upon the discharge of a cup in the above manner below the fluid discharge tube D, fluid is permitted to discharge into the cup from a tank E, it being understood that in 25 practise the cup is supported by suitable means permitting the operator to grasp the same and easily remove it when filled. This fluid discharge is under control of a measuring device consisting of a hollow valve F 30 reciprocable within a similarly cylindrical valve casing G having its inner rear end securely locked through the wall of the tank E as at G' and opening into the same.

The inner or rear end of the measuring 35 valve F is closed and has around the same a forwardly facing bevelled valve rib F' which, in the normal position of the parts, seats against the inner end of the casing G. Adjacent to this end, the valve F also has an 40 annular series of fluid inlet openings F² which are exposed to the interior of the tank E when the valve is shifted inwardly or rearwardly.

The forward end of the casing G threads 45 into the upper sleeve D' of the discharge tube or spout D and presents an edge G² for engagement by the annular valve rib F³ at the forward end of valve F, which rib is preferably formed in connection with a forwardly projecting axial valve stem F⁴. Near 50 its said forward end valve F has a second annular series of openings F⁵, these being for the discharge of fluid and being for this purpose disposed forwardly of the casing G 55 when the valve is in forward position so as to permit the contents of the hollow valve to flow into the sleeve D' and thus from the discharge spout D.

As shown more particularly in Figures 1 60 and 2, the sleeve D' of the discharge spout has oppositely outstanding horizontal side pieces 21 and 22, the former elongated forwardly along one side of the plane of the valve casing G and the latter secured to a 65 horizontal bracket 23 at the rear of the cup

dispensing apparatus A. To the side piece 21 a pair of plunger guide plates 24 and 25 are secured along one side and these guide plates are so spaced as to form between them an inverted U-shaped guide channel for the 70 similarly shaped plunger 26 having at its forward end a hand piece 27 facilitating manual actuation of the plunger both rearwardly and forwardly.

There is also secured to the side piece 21 75 a supplemental frame including cross members 28 and 29 extending over the plunger guide plates 24 and 25 at longitudinally spaced points, and a laterally outstanding bearing support 30. The forward cross 80 member 29 serves as a support for the coin actuated plunger controlling detents while the rear cross member 28 supports a cross pin 31 serving as a fulcrum for a longitudinal coin ejecting lever 32 resembling a walking 85 beam, see Figures 5 and 7.

By reference to Figure 6, it will be seen that the plunger 26 has a coin receiving aperture 33 at the forward end of a central longitudinal slot 34 and that it has slots 35 parallel 90 with, and at opposite sides of, slot 34. Slots 35 receive the lower ends of an inverted U-shaped latch 36 which as shown in Figure 3 is mounted to shift vertically in the frame member 29 with its cross piece below a press bar 37 and above a latch releasing detent 38 whose lower end is disposed in the central slot 34. The lower end of detent 38 is bevelled rearwardly so that a coin in the aperture 33 engages its lower end and elevates the same and thus the latch 36 so that the plunger may be thrust rearwardly. The press bar 37 above referred to is slid able at its ends upon upright guide rods 39 fixed at their lower ends in the cross frame 29 and rigidly connected at their upper ends by a cross bar 40. Springs 41 are coiled around the rods 39 and compressed between the press bar 37 and the cross bar 40. The cross bar 40 also has a depending bracket portion 42 between the rods 39 which serves as a support for a pivoted rocking member 43 constituting a lock and having a pin movably engaging the slotted end 44 of the controlling lever 15 before referred to. This lock member 43 is normally retained by gravity in the horizontal inactive position shown in Figure 3, but when the weight C engages and depresses the adjacent end of the controlling lever 15, its slotted end 44 will be raised, thus swinging the lock 43 to a vertical position wherein it prevents the press bar 37 from rising and in this way holds the latch 36 in connection with the plunger 26. Thus the plunger can not be actuated when the cup magazine or 110 holder is empty.

Immediately in front of the latch releasing detent 38 and above an opening 45 in the lower guide plate 25 of the plunger, a second detent 46 is slid able vertically in a tu- 115 120 125

bular upright bearing 47 of the cross frame 29. The upper end of this detent is engaged by a spring 48 held in place by a threaded cap plug 49 and the lower end thereof is bevelled forwardly or in a direction opposite to that of the detent 38. The opening 45 is slightly smaller than the coin aperture 33 and is located immediately to the rear thereof when the plunger is in its forward position. Thus if a coin of less than the proper size is placed in the aperture 33 it will be engaged by the detent 46 and will be thrust downwardly through the opening 45 and rejected in this way. Again should a slug with a central opening be used the detent 46 will drop into the opening of the slug before the detent 38 is engaged thereby and the plunger will be locked against further inward or rearward movement.

The guide plates 24 and 25 of the plunger 26 are slotted rearwardly of the cross frame 29 so as to accommodate a vertical operating pin 50 whose upwardly projecting portion in the rearward movement of the plunger 26 engages and elevates the rear tail portion of the coin ejecting lever 32 so as to force the forward nose of this lever downwardly to engage the coin and depress the same out of the coin aperture 33 after it passes the detent 38 as shown in Figure 7. This prevents repeating by the use of a coin whose edge has been burred to stick in the coin aperture.

The depending portion of the pin 50 extends through the laterally elongated slot 51 intermediate the ends of the valve-actuating lever 52, the outer end of which is pivoted upon a pin 53 mounted through the outer end of the before mentioned frame arm 30. The inner end of this lever 52 has a yoke 54 engaging a grooved collar 55 upon the forward end of the valve stem F⁴. Lever 52 also has intermediate its ends a pivot pin 56 depending through the slotted end of a spring-controlling lever 57 fulcrumed at 58 upon a frame member 59 beneath the plunger guide. The other end of lever 57 is connected to one end of a retractile coil spring 60.

The plunger pin 50 also depends through the inner longitudinally slotted end 61 of a second spring controlling lever 62 which is fulcrumed adjacent to its outer end upon the pin 53. The outer end of lever 62 is angled somewhat and connected to the opposite end of spring 60 and also to one end of a spring 63 whose other end is connected to the rear end of the plunger guide as shown in Figure 1. It is thus obvious that when the plunger is moved rearwardly the valve actuating lever will also be moved rearwardly and the spring engaging ends of levers 57 and 62 will be shifted forwardly beyond a line connecting the pivots 53 and 58 so that in the latter portion of its rearward or inward

movement, the valve F will be accelerated to the liquid receiving position and its valve rib F³ firmly engaged with the forward end G² of the valve casing, by the tension of spring 60. Likewise the movement of the valve stem and valve is accelerated when the plunger is pulled forwardly, since the spring 60 is shifted rearwardly to the position shown in Figure 8, so that the valve will be snapped to the liquid discharge position and its rear valve rib F' tightly engaged with the rear end of the casing G. This arrangement insures snug non-leaking engagement of the valve in both positions and the discharge of the same quantity of fluid at each operation so of the plunger.

The upper portion of the plunger pin 50 also works in a slotted arm 64 whose rear end is pivoted at 65 to one end of a lever 66 fulcrumed upon an upstanding pin 67 and 85 having its other end pivotally connected to the rear end of a connecting arm 68. The forward end of this connecting arm 68 is pivotally connected to the crank arm A' of the cup dispensing mechanism, as most plainly shown in Figure 1 and has an upstanding pin 69 to the upper end of which the forward end of a connecting rod 70 is joined.

Across the rear portion of the cup dispensing mechanism a bracket 71 is securely fastened thereto and to the before-mentioned horizontal bracket 23. The bracket 71 has at its opposite sides bearings 72 for a shaft 73 provided at one end with a crank 74 to which the rear end of connecting rod 70 is 100 joined. The other end of shaft 73 carries a cam 75 disposed between, and operating against, the vertically spaced rollers 76 and 77 of a vertically movable slide plate 78 supported by the bracket 71. The slide plate 105 78 has a socket member 79 in which one end of a connecting rod 80 is engaged. The other end of this connecting rod engages a socket member on the crank arm 20 of the cup protecting member 18 so that in the rearward movement of the plunger at the time the cup dispensing apparatus is actuated, the member 18 will be shifted downwardly to its inactive position shown in dotted lines in Figure 9.

It is apparent from the foregoing that my invention makes it necessary to insert the proper coin in the coin aperture of the plunger before the latter can be forced rearwardly upon the first half of its full stroke, and that an apertured slug will be arrested and a slug or coin of smaller than the required size will be rejected. During this half of the stroke, the cup dispensing mechanism will be actuated and a cup dropped beneath the fluid discharge spout and in addition to this the measuring valve will be shifted to its inner position where it fills with fluid from the tank. Thus upon pulling the plunger forwardly the valve will be shifted to discharge 125 130

position, the cup previously dropped will be filled and the protecting member 18 restored to its active position shown in full lines in Figure 9.

5 It becomes obvious from the foregoing that my invention provides a simple, strong and durable mechanism capable of installation and removal as a unit which greatly facilitates repair and substitution of parts 10 as well as careful effective assembly and adjustment in the first instance, as well as a mechanism which is proof against the unwarranted operation so common in devices of a similar general nature now in use.

15 What I claim is:

1. In a mechanism of the character described a plunger, a controlling latch therefor, a latch releasing detent, a locking member shiftable into the path of releasing movement of said latch, and gravity means for so shifting said locking member.

2. In a coin controlled mechanism, a plunger, a controlling latch therefor, a coin actuated detent for releasing said latch, connections to lock said latch against releasing movement and a gravity member for actuating said locking connections.

3. In a coin controlled mechanism, a plunger having a coin aperture and a slot extending therefrom, and also having slots upon opposite sides of the first slot, a U-shaped latch having its lower ends disposed in the latter slots, a coin actuated detent in the first slot movable upwardly against a portion of said latch to elevate and release the latter, and a second detent forwardly of said first detent and in the path of travel of the coin in said aperture, said second detent acting as a supplemental latch and to prevent 40 actuation of the first detent by an apertured slug.

4. In a coin controlled mechanism, a plunger having a coin aperture and a slot extending therefrom, and also having slots upon opposite sides of the first slot, a U-shaped latch having its lower ends disposed in the latter slots, a coin actuated detent in the first slot movable upwardly against a portion of said latch to elevate and release 50 the latter, and a second detent forwardly of said first detent and in the path of travel of the coin in said aperture, and a support for said plunger having an opening below said second detent of smaller diameter than 55 said coin aperture.

5. In a coin controlled mechanism, a plunger having a coin aperture and a slot extending therefrom, and also having slots upon opposite sides of the first slot, a U-shaped latch having its lower ends disposed in the latter slots, a coin actuated detent in the first slot movable upwardly against a portion of said latch to elevate and release 60 the latter, and a second detent forwardly of 65 said first detent and in the path of travel of

the coin in said aperture, said detents having oppositely bevelled lower ends and said second detent being normally supported upon the face of the plunger.

6. In a coin controlled mechanism, a plunger having a coin aperture, a support therefor, a cross frame on said support having upright bearing, a U-shaped latch member having its extensions depending through certain of said bearings to engage the plunger, a detent in another of said bearings and having its upper end engaging the cross bar of said latch, the lower end of said detent being bevelled for actuation by a coin in said aperture, uprights carried by said frame, a press bar guided by said uprights and resting on said detent, springs engaging said press bar, a cross piece connecting the uprights, and a pivoted member supported by said cross piece and normally standing parallel to and spaced from said press bar, and gravity controlled means for shifting said pivoted member to a position at right angles to and engaging the press bar whereby to prevent effective movement of said detent. 90

7. In a coin controlled mechanism, a plunger having central and side slots and a coin aperture in line with the center slot, a latch having portions extending into the side slots, a detent engaging a portion of said latch and depending into the central slot for actuation by a coin to displace the latch, and a combined coin displacing and plunger latching detent forwardly of said first named detent. 100

8. In a coin controlled mechanism, a plunger having central and side slots and a coin aperture in line with the center slot, a latch having portions extending into the side slots, a detent engaging a portion of said latch and depending into the central slot for actuation by a coin to displace the latch, a combined coin displacing and plunger latching detent forwardly of said latch displacing detent, and a coin displacing member actuated by the plunger and disposed rearwardly of the latch displacing detent. 105

In testimony whereof I affix my signature.

HARRY M. HENDERSON.
